ILLUMINATED DIAL

Elliott W. Gardinor, Binghamton, N. Y., assignor to International Business Machines Corporation, New York, N. Y., a corporation of New York

Application September 10, 1940, Serial No. 356,148

3 Claims. (CL. 240—2.1)

This invention relates to a clock dial structure and means for illuminating the same.

The general object of the instant invention is to provide improved illumination for a clock dial by special arrangement of a light source and light directing surfaces to effect a substantially even distribution of light over the dial.

More specifically, an object of the invention resides in the provision of illuminated gas-filled tubing located between the dial and the hands of the clock to prevent the clock hands from casting shadows on the surface of the dial.

Another object is to provide a clock dial having a special curvature to aid in reflecting the light from a source mounted behind the clock hands and adjacent the central portion of the dial.

It is also an object to provide an opal glass disk novelly mounted between the light source and the clock hands for diffusing the light passing therethrough so as to lend a more pleasing appearance to the illuminated clock dial.

The invention contemplates employing a dish shaped dial for aiding in directing the light more effectively from a circular tube filled with a suitable gas, such as neon, and mounted directly in front of the central portion of the dial. An opal glass disk is placed in front of the tube and the clock hands are located in front of the disk. With this arrangement, part of the light diffuses through the disk and part of the light strikes the curved surface of the dial and is reflected outwardly. In view of the fact that the clock hands are mounted in front of the light source and the disk, there can be no shadows cast by these hands in the direction of the dial. The rear lighting of the clock hands makes their position and identification more readily determinable at a glance.

Other objects of the invention will be pointed out in the following description and claims and illustrated in the accompanying drawing, which discloses, by way of example, the principle of the invention and the best mode, which has been contemplated, of applying that principle.

In the drawing:

Fig. 1 is a face view of the clock.

Fig. 2 is a section taken on line 2—2 of Fig. 1.

Fig. 3 is a sectional detail view showing the connection between the dial and a rim which also holds the customary glass cover protecting the clock face.

Referring now to the drawing, 10 represents a drum containing the necessary clock mechanism for driving stub shafts 11 and 12 to which are attached an hour hand 13 and a minute hand 14, 55

respectively. The clock mechanism in itself forms no part of the present invention.

A plate 15, integral with the right end of the drum as viewed in Fig. 2, is provided with mounting brackets 16 bolted to the plate at spaced intervals around its periphery. Bolts 17, which are employed to connect the brackets with the plate, also serve to fasten an opal glass disk 18 to the supporting plate 15 with the cooperation of nuts 19 and 20. Disk 18 is formed with a central hole to provide clearance for shafts 11 and 12. The thicknesses of brackets 16 and of the nuts 20 cause a space to be left between the disk 18 and the supporting plate 15 which helps provide clearance for a circular glass tube 21 placed immediately behind the disk 18 and directly in front of a clock dial 22. The tube 21 is filled with gas, such as neon, and is illuminated in a well known manner by application of a suitable difference of potential to terminal members 21a and 21b which pass through holes in the dial 22 and help support the tube in the position shown in the drawing. The clock dial itself is secured to the brackets 16 by bolts 23 cooperating with nuts 24. A circular ring 25 serves as a backing for the dial to strengthen the bolted connections with the brackets.

The clock dial 22 is made concave, resembling in shape an ordinary dish. The reason for providing such a curvature to the dial is to improve the reflection of light rays from illuminated tube 21 which impinge on the surface of the dial. A considerably larger portion of the light from the tube reaches dial 22 directly by virtue of its curvature than would fall on a flat dial mounted at the same place.

A suitable rim 25 is provided to cover the outer edges of the dial and of a protective glass 26. The glass and the dial are clamped together at the edges by the cooperation between the front of the rim 25 and spring clip 27 carried by the rim.

A substantially even distribution of light on the dial is obtained by the above described structure. The light which tends to come directly out to the front from tube 21 is diffused by the opal disk 18. The light which tends to directly seek out the rim 25 is intercepted by the curved surface of the dial 22. By locating the light source in the manner shown, rather than in the rim as is customarily done with a tubular light source, is to greatly reduce the shaded portion around the center of the dial. In the arrangement presented herein, the light source is considerably closer to the center of the dial and the light is

softened by diffusion. As the clock hands 13 and 14 rotate in front of the light source and the diffusing disk, they cannot cause shadows to fall on the clock dial.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. A clock case construction comprising, in combination, a supporting plate at the rear of said case, a concave dial secured to said plate, a luminous gas tube positioned about the center of the dial and intermediate the center of the dial and its edges, an opalescent element carried by the supporting plate and spaced therefrom so as to be located immediately in front of the tube, and clock hands supported in front of the element for cooperation with the dial.

25

2. A clock case construction comprising, in combination, a supporting plate at the rear of said case, a concave dial secured to said plate, a circular tube containing luminous gas positioned about the center of the dial, the diameter of the dial being substantially greater than the diameter of the circle formed by the tube, an opalescent material carried by the supporting plate and spaced outwardly therefrom so as to be located in front of the luminous gas tube, and clock hands supported in front of the material for cooperation with the dial.

3. In combination, a supporting plate, a concave clock dial fastened to said plate, a luminous gas tube located in front of the dial and adjacent the central portion of said dial, an opalescent material carried by the supporting plate spaced therefrom a distance sufficient to locate the material in front of the tube, clock hands supported in front of said material and cooperating with the dial, a glass panel in front of the hands for covering the dial, and a rim around the edge of the dial for holding the outer edges of the material against said dial.

ELLIOTT W. GARDINOR.
